BOILER INSTALLATION AND METHOD OF
OPERATION

Kurt Toensfeldt, Port Washington, N. Y., assignor
to International Combustion Engineering Corporation,
New York, N. Y., a corporation of
Delaware

Application November 2, 1932, Serial No. 640,735

4 Claims. (Cl. 122—235)

This invention relates to boiler installations and method of operation, and is particularly useful where a superheater, a reheater and an air heater are employed.

5 The nature and objects of the invention will be understood from the following: In present practice in high capacity boiler installations, superheats and reheat rise as high as 800 to 825° F., requiring a full flow of gas over the super-
10 heater and the reheater. Due to the overheating which occurs at high rates, it is necessary to by-pass some of the gas in order to hold the superheat or the reheat down to normal, this being desirable not only from the standpoint of efficiency but from the standpoint of the life of the
15 superheater and the reheater tubes.

It has been known to by-pass gas in such installations, but I propose to accomplish this in a manner whereby a maximum-sized air heater, required for efficient operation of the unit, may be employed; whereby the by-passed gas mingles with the gas leaving the reheater at approximately the same temperature instead of at markedly different temperatures which is undesirable; and whereby the amount of convection surface needed to properly cool the by-passed gas is small and makes for an economical arrangement of parts. Also by my invention the unit may handle slightly more flue gas per unit
30 for the same temperature of gas entering the air heater with consequent increase in steam output and increase in efficiency, as compared to installations in which no by-passed gas is passed over convection surfaces.

35 How the foregoing, together with such other objects and advantages as may hereinafter appear or are incident to my invention, are realized is illustrated in preferred form in the accompanying drawings, wherein—

40 Fig. 1 is a vertical section through a boiler installation embodying my improvement, and

Fig. 2 is a section taken on the line 2—2 of Fig. 1.

In the combination of parts constituting my improved installation I provide a boiler the tubes of which are arranged in the form of a six-sided box to provide a combustion chamber A. The boiler has an upper steam and water drum 7 and a mud drum 8 therebelow, the tubes defining the combustion space being connected so as to receive their water supply from the mud drum and to deliver into the steam and water drum. At the rear of the combustion chamber a baffle 9 is associated with the tubes defining the rear wall of the combustion chamber, said baffle extending up-

wardly from the drum 8 to a point short of the steam and water drum 7. Above the spaced tubes 10 which are at the top of the combustion chamber is a space B for the superheater 11. Horizontal baffle means 12 are associated with the tubes 10 and the baffle 9 so as to normally direct all of the gaseous products of combustion leaving the combustion space over the superheater 11. Forming part of the baffle 12 is a damper 13 operated in any preferred manner from the exterior of the setting and by which a portion of the gases may be by-passed around the superheater. The side wall tubes 14 are carried upwardly to line the sides of the space in which the superheater is located, this space being further lined at the top 10 by the tubes 15 which connect with the steam and water drum 7 and constitute the delivery tubes for the side wall tubes 14. The tubes 10 at their rear portion rise upwardly for connection with the steam and water drum 7. Thus the super-
15 heater is bounded on five sides by evaporating tubes which tend to prevent overheating and maintain the superheater normal, except at periods of high rating when the damper 13 is opened in an amount sufficient to by-pass enough gas to 20 prevent rise in superheat above normal. Spaced apart from the few tubes with which the baffle 9 is associated, is a group or bank of convection tubes 16, the number of which is small, these tubes constituting the downcomers from drum 7 25 to drum 8. With the rear tubes of the bank 16 is associated a baffle 17, this baffle extending short of the steam and water drum in order to permit flow of gases from the superheater space into the offtake C in which the reheater elements 18 are 30 located. Baffles 19, preferably three in number, extend rearwardly from the baffle 9 to the front tubes of the bank of tubes 16 and at the lower end of the baffle 17 there is a damper 20 controlling the outlet passage 21 at the bottom of the bank 35 of tubes 16.

The damper 20 is normally closed, but under conditions of operation when there would be a tendency for the temperature of reheat to rise above normal, the damper 20 is opened to an 45 extent sufficient to by-pass the required amount of gas to maintain normal reheat temperature. Gas will by-pass upon opening of the damper 20 because the resistance to flow through the bank of tubes 16 is less than that through the 50 reheat elements. The amount of convection surface presented by the convection bank of tubes 16 is, therefore, approximately just sufficient to lower the temperature of the gases which leave the bank to the temperature of the gases 55

leaving the re heater elements at normal temperature for reheat. The gas is, therefore, mingled at the same temperature.

The air heater 22 is of maximum size to give 5 the final exit temperatures of the gas, and thus it will be seen that the amount of convection surface in the bank of tubes 16 does not have to be unduly large—in fact no larger than that required to lower the temperature of the by-passed 10 gas to that of the gas leaving the re heater. Thus economy and efficiency not only from the standpoint of the air heater, but also from the standpoint of the convection bank of tubes, are obtained. It is much more economical to provide 15 convection surface by way of air heating surface than it is by way of providing convection boiler tubes. In addition it will be seen that the arrangement of convection tubes is simple and economical, and because of the small number, 20 adequate ligament efficiency can be obtained and the installation operated on high pressures. The use of a radiant heat boiler also makes it possible to reduce the amount of convection surface over that which would otherwise be required.

25 I prefer to so proportion the various surfaces,— save at periods of higher rating, when there is a tendency to over superheat and over reheat—to secure the following gas temperatures; leaving the furnace 1810°; entering the superheater 30 1720°; leaving the superheater 1305°; entering the re heater 1185°; leaving the re heater 775°. The installation as shown is calculated to operate on pressures of 1400 pounds.

I claim:—

35 1. In combination, an upper steam and water drum, a mud drum therebelow, boiler tubes defining combustion space for the boiler connected for supply and delivery to said drums respectively, a superheater above the combustion space, 40 there being but few boiler tubes interposed between said superheater and said combustion space, means for by-passing a portion of the gases leaving the combustion space around said superheater, an offtake serially following the 45 superheater, a re heater therein, a bank of convection tubes connecting the drums, means providing a pass for said convection tubes in parallel with the re heater for gas flow and which offers less resistance to gas flow than that of the 50 re heater, a substantially full sized air preheater serially following the re heater, and a damper controlling the pass of the convection bank, the amount of surface presented by the convection

bank being sufficient to reduce the temperature of the by-passed gases approximately to that of the gases leaving the re heater.

2. In combination, a furnace-shaped boiler, a superheater in an upper portion of the boiler over which products of combustion pass in leaving the combustion chamber of the boiler, a gas offtake joining the boiler adjacent the superheater, adjustable means for by-passing gases around the superheater to the offtake, a pair of 10 offtake passages having their entrance ends both adjacent said point, an additional offtake passage into which said pair of passages deliver, an air heater in the additional passage, a steam 15 heater in one passage of said pair, boiler tubes in the other passage of said pair, the boiler tubes being arranged to offer less resistance to gas flow than the steam heater, and adjustable means for controlling the flow of gases through the passage containing the boiler tubes. 20

3. In combination, a furnace shaped boiler having a combustion chamber at least in large part defined by tubes providing the major portion of the heat absorbing surface of the boiler proper, convection tubes also associated with said boiler, a gas offtake disposed beyond the major portion of the boiler with respect to gas flow, the offtake including a pair of passages arranged in parallel with respect to gas flow in an advance portion of the offtake, said offtake further including an additional passage into which said pair of 25 passages deliver, an air heater in said additional passages, a re heater in one passage of said pair, said convection tubes being located in the other passage of said pair, and means for controlling flow of gases through the passage containing the convection tubes. 30

4. The method of operating a boiler installation having an offtake with a re heater in an advance portion thereof and an air heater in a succeeding portion thereof, and further having a by-pass around said re heater with convection surfaces therein; which method includes passing substantially all of the gases through the re heater at substantially normal ratings and, at 45 higher than normal ratings, passing gases through said by-pass in amounts such as to maintain the reheat temperature substantially the same as for the normal ratings, so as to reduce the by-passed gas temperature approximately to that of the gases leaving the re heater. 50
